UNITED STATES PATENT OFFICE.

GEORGE C. ANDREWS, OF MINNEAPOLIS, MINNESOTA.

GARBAGE-BURNER.

1,284,971.

Specification of Letters Patent. Patented Nov. 19, 1918.

Application filed September 27, 1916. Serial No. 122,394.

To all whom it may concern:

Be it known that I, GEORGE C. ANDREWS, a citizen of the United States, residing at Minneapolis, in the county of Hennepin and 5 State of Minnesota, have invented certain new and useful Improvements in Garbage-Burners; and I do hereby declare the following to be a full, clear, and exact description of the invention, such as will enable 10 others skilled in the art to which it appertains to make and use the same.

My invention has for its particular object the provision of an improved garbage burner that is also an efficient hot water heater; and to such ends, generally stated, 15 the invention consists of the novel construction and combination of parts hereinafter described and defined in the claims.

In the accompanying drawings which 20 illustrate the invention, like characters indicate like parts throughout the several views.

Referring to the drawings:

Figure 1 is a perspective view with some parts broken away and some parts sectioned, 25 showing the improved garbage burner and hot water heater; and

Fig. 2 is a horizontal section taken on the line 2—2 of Fig. 1.

The walls of the burner are made up of 30 an outer shell 3 and an inner shell 4, both of which are preferably cylindrical. The outer shell 3, at its upper end, is closed by a head 5, and the inner shell 4, at its upper end, is closed by a head 6. The two 35 shells are spaced so as to form a thin water chamber 7, the lower portion of which is tightly closed by a spacing strip 8 riveted to the two shells. The water chamber is also extended between the heads 5 and 6. 40 The lower portion of the outer shell 3 is extended downward to form an ash pit below the water chamber 7, and a door 9 opens into this ash pit. Preferably, several doors 45 10 and 11 open through the water chamber to the interior of the casing formed by the two shells. A smoke pipe 12, which has an upturned inner end, leads outward through the upper portion of the casing made up of the two shells. The inner end of the smoke 50 pipe is turned upward but terminates considerably below the head of the inner shell 4, so that the products of combustion will first strike the said head and will then be deflected and drawn downward and outward through the smoke pipe.

The grates 12 are shown as mounted in a

ring 13 rigidly secured to the lower portion of the inner shell 4.

As shown, a plurality of hot water pipes 14 extend from the upper portion of the 60 water chamber 7, and a plurality of cold water return pipes 15 lead back to the bottom of the said water chamber.

A multiplicity of diametrically extended approximately horizontal water tubes 16 extend through the inner shell 4 and connect opposite sides of the water chamber 7. The outer shell 3 is provided with tube passages normally closed by plugs 17, but which, when opened, permit access to the ends of 70 the corresponding tube 16 for the purpose of cleaning or repairs. Obviously, when the plugs 17 are removed, the tube cleaner may be run straight through the respective tubes 16. These tubes 16 perform two important functions. In the first place, they 75 give very greatly increased heating surface exposed to the flames or products of combustion; and in the second place, their spiral arrangement affords a kind of spiral 80 stair or ladder grate on which the garbage waste paper, and the like, (which are usually commingled) are held in a spiral stack, and affords a spiral flame passage under the same, so that gradual drying and burning is 85 accomplished while the stack gradually condenses and lowers with a progressive action.

The upper door 10 affords means for introducing the garbage into the upper portion of the combustion chamber above the spiral stack tubes, while the door 11 affords access to the lower portion of said combustion chamber at a point below the ladder grates and above the lower grate, so that inspection may be made at any time or an auxiliary coal or wood fire may be started on the lower grate to assist in drying and burning the garbage or heating water.

The device described, broadly speaking, is 100 a stove. It is especially adapted for the burning of garbage, and for the utilization of heat thereby produced for heating water. It may, of course, be made of any desired size and used for many purposes.

What I claim is:

1. A stove having a spiral grate and a spiral combustion chamber following the under side thereof, the shell of said stove having a door closed upper opening above said 110 spiral grate, and having a lower door closed opening below said lower grate.

2. A stove having a lower grate and above the same a ladder-like spiral auxiliary grate and a spiral combustion chamber following the under surface thereof, the shell of said stove having an upper door closed opening above said spiral grate and having a lower door closed opening above said lower grate and below said spiral grate.
3. A stove having a surrounding water jacket and a bottom grate, and provided above its grate with spirally arranged water tubes connecting diametrically opposite portions of said water jacket and forming a ladderlike spiral auxiliary grate, a fuel door

opening through the upper portion of said water jacket, the said water jacket being extended over the top of the combustion chamber, and a smoke pipe leading through the upper portion of one side of said water jacket and having an upturned inner end terminated below the top of the combustion chamber.

In testimony whereof I affix my signature in presence of two witnesses.

GEORGE C. ANDREWS.
